UNITED STATES PATENT OFFICE.

LESTER C. DUNCAN, OF LENIA, IDAHO.

SPEEDOSCOPE.

1,105,411.

Specification of Letters Patent.

Patented July 28, 1914.

Application filed March 31, 1913. Serial No. 757,751.

To all whom it may concern:

Be it known that I, LESTER C. DUNCAN, a citizen of the United States, residing at Lenia, in the county of Bonner and State 5 of Idaho, have invented new and useful Improvements in Speedoscopes, of which the following is a specification.

My invention relates to an improved form of speedoscope and has as its principal object 10 the provision of means for indicating the speed at which a vehicle was traveling just before it was stopped.

A second object of my invention is to provide means whereby an alarm is rung when 15 the vehicle reaches a predetermined speed.

The final object of my invention resides in the particular arrangement and combination of parts hereinafter described.

In the accompanying drawings:—Figure 20 1 is a side elevation of my improved device. Fig. 2 is a front elevation of the device shown in Fig. 1. Fig. 3 is an elevational view of the interior of my device the front covers being removed and certain parts of 25 the mechanism being removed for purposes of clear illustration, the parts being shown in the position when at rest. Fig. 4 is a view similar to Fig. 3 but showing the parts in a position as when the device is being operated. Fig. 5 is an elevational view taken 30 from the same position as Fig. 1, but parts being broken away and parts being shown in section for purposes of illustrating the interior mechanism. Fig. 6 is a front view 35 of my device, the glass cover and hands having been removed. Fig. 7 is a detail perspective view showing certain of the gear trains used to operate the device. Fig. 8 is a detail perspective view of the dog used in 40 the recording apparatus. Figs. 9 and 10 are detail views of the indicating and recording hands, respectively.

In the separate views, the same part is indicated by the same reference character.

45 Referring more particularly to the drawing, 1 is an outer case, preferably cylindrical in form, provided with a rear cover not shown, and a front opaque cover 2 shown in Fig. 5. In front of the opaque cover 2 is a 50 glass cover 3.

The spindle 10 is mounted within the case 1 as shown in Fig. 5, there being ball bearings provided at each end of the spindle. It 55 is intended that the spindle 10 shall be connected by suitable mechanism with the axle of the vehicle whose speed it is desired to

read and record. Slidably mounted on the spindle 10 is a sleeve 11 provided with an outer serrated surface. A spring 15 is provided which is coiled about the spindle 10 60 and which acts normally to move the sleeve 11 upward into the position shown in Fig. 3. I provide means, however, adapted when the spindle 10 is rotated, to overcome the force of the spring 15 and these means are 65 preferably two rings such as 13 pivoted to the spindle 10 by means of a pin shown at 14 in Fig. 4, said pin extending at right angles to the spindle 10. The rings 13 are connected to the sleeve 11 by means such 70 as links 12—12, said links having pivotal connection with both the rings and the sleeve. As shown in Fig. 3, the normal position of the sleeve is such that the rings 13 are drawn into a position oblique to the 75 spindle 10, but as the spindle is revolved centrifugal force tends to throw the rings 13 into a plane at right angles to the spindle, it being understood that one of the rings 13 is larger than the other so that the two may 80 revolve about the same pivot without interference. As the rings move from the position shown in Fig. 3 to that shown in Fig. 4 the sleeve 11 is drawn downward against the action of the spring 15. I provide a 85 pinion 16 which meshes with the serrations on the outer surface of the sleeve 11. Pinion 16 is clearly shown in Fig. 7 but in Fig. 5 it is covered by the sleeve 11. Pinion 16 is carried on the shaft 18 and said shaft also carries a gear 19 which meshes with gear 20 on the shaft 21. The shaft 21 projects through the front cover 2 and carries at its outer end a pointer 17 which cooperates with the scale 17^a shown in Fig. 2, in order to indicate 90 the speed at which the vehicle is moving. As clearly shown in Fig. 9 the pointer 17 is keyed rigidly to the shaft 21 by the key 5. By the mechanism just described it will be seen that the movement of the rings 13 is 95 transmitted to the pointer 17, and that said mechanism and counter, together with the scale, constitute the indicating portion of my device.

In order to show the speed at which the 105 vehicle was traveling shortly before it stopped, or in other words provide a registering means in connection with my speedoscope, I provide on the upper end of the spindle 10 a worm 28 which meshes with a 110 gear 29 shown in Fig. 7 but obscured in Fig. 5. Gear 29 is carried on a shaft 30 and said

shaft also carries a worm 32 which meshes with a gear 31 on a shaft 33. Shaft 33 carries a worm 34 which meshes with a gear 35. Gear 35 is mounted on a shaft 36 which 5 is parallel to but separate from the previously mentioned shaft 18. The line of division between the shafts 18 and 36 is indicated in the broken away portion of Fig. 5. The shaft 36 also carries a gear 37 which 10 meshes with a gear 38. The gear 38 is fastened to the side of a disk 39 and both 38 and 39 are loose upon the shaft 21. On the opposite side of the disk 39 from the gear 38 said disk is provided with a series of 15 notches such as 26. Moreover a sleeve 24 is loosely mounted on the shaft 21 and provided with an arm extending parallel to the face of the disk 39, said arm being provided with a dog 25 which is adapted to engage 20 the teeth 26 so as to drive the sleeve 24 in one direction, a spring 27 being provided which bears against the inner face of the head 2 and against the sleeve 24 so that dog 25 is always held against the teeth 26. How- 25 ever, the spring 27 is a light one so that dog 25 may be caused to slide over the teeth 26 without the expenditure of much force. The sleeve 24 projects through the head 2 and has rigidly mounted thereon the pointer 23. 30 The pointer 23 is provided with a pin 22 which projects up into the path of the pointer 17 so that as the pointer 17 moves from the zero position, the pointer 23 is pushed in front of it. Now it must be un- 35 derstood that the gear operated from the worm 28 through the shafts 30, 33 and 36 is designed to turn the disk 39 and consequently the sleeve 24 and the pointer 23 in a direction opposite from that which it is 40 turned by the pointer 17. Consequently if, after having moved the pointer 23 the pointer 17 withdraws from its outermost position, the gearing just described will im- 45 mediately tend to turn the pointer 23 back toward zero position. Consequently the pointer 23 tends always to follow the pointer 17, but if the vehicle is stopped, the pointer 17 will immediately drop back to zero where- 50 as the gear operating the pointer 23 having been stopped, the latter pointer will remain so as to register the speed at which the machine was traveling immediately before it was stopped.

In order to warn the driver of a vehicle 55 when he is exceeding the speed limit, I provide an adjustable alarm. Said alarm comprises two standards such as 60 which project from the rear cover of the case 1. Carried by the standard 60 is a vertical rod or 60 shaft 41 which is provided with a rack 40. The rod 41 carries a finger 42 which is mounted directly on a pivot pin 46 carried in an insulating bushing 43. A spring 47 normally swings the arm or finger 42 into 65 the position shown in Fig. 3, its further

movement being prevented in one direction by the pin 47^a, but it will be seen that the arm is free to move downward when the tension of spring 47 is overcome by contact between the end of the arm and the collar 51 70 on the sleeve 11. Now the arm 42 is connected directly to a wire 45 which forms part of a circuit including any suitable source of current and the electric bell 44, it being understood that the end of the circuit 75 remote from the arm 42 is grounded to the case 1. Consequently, when the sleeve 11 is moved by the action of the rings 13 so that the collar 51 contacts with the arm 42, the bell is rung so as to warn the driver. The 80 arm 42 may be set so that the alarm will be sounded at any desired speed and for this purpose I provide a gear 48 which meshes with the rack 40 and is carried by a shaft 61 extending through the side of the case 1. 85 At the outer end, the shaft 61 carries a knurled nut 49 by which it may be turned and a hand or pointer 50 is also carried on said shaft on the outside of casing, said pointer being designed to coöperate with the 90 scale such as 62 so as to show the speed for which the alarm is set.

It will be understood that while I have shown and described herein the preferred form of my invention, various modifications 95 and rearrangements thereof may be made without departing from the spirit of my invention, and that I contemplate all such modifications as are mechanically and electrically equivalent to the arrangement shown 100 and described herein. It will be further understood that parts of my invention may be used without using the whole.

Having thus described my invention, what I claim is:—

1. A speedometer apparatus comprising in combination, a movable pointer for indicating the speed of a vehicle, mechanism for operating said pointer, a second pointer adapted to be moved by said first mentioned 110 pointer in one direction, and means normally tending to move said second mentioned pointer in the direction opposite to that in which it is moved by said first mentioned pointer.

2. A speedometer apparatus comprising in combination, a revoluble spindle, centrifugally operated weights pivoted to said spindle, a pointer for indicating the speed of a vehicle, mechanism for transmitting the 120 movement of said weights to said pointer, a registering pointer adapted to be moved in one direction by said first mentioned pointer, and mechanism geared to said spindle adapted to move said second mentioned 125 pointer in a direction opposite to which it is moved by said first mentioned pointer, said last mentioned mechanism being provided with a sliding connection whereby said second mentioned pointer is permitted 130

to be turned back with the first mentioned pointer.

3. A speedometer apparatus comprising in combination, a revolute spindle, centrifugally operated weights pivoted to said spindle, a pointer for indicating the speed of a vehicle, mechanism for transmitting the movement of said weights to said pointer, a registering pointer adapted to be moved in one direction by said first mentioned pointer, and mechanism driven from said spindle at a relatively low speed and adapted to move said registering pointer in a direction opposite to which it is moved by said first mentioned pointer.

4. A speedometer apparatus comprising in combination, a revolute spindle, centrifugally operated weights connected to said spindle, a pointer for indicating the speed

of a vehicle, a stem on which said pointer is mounted, mechanism for transmitting the movement of said weights to said stem, a sleeve surrounding said stem, a registering pointer fixed to said stem, means for moving said registering pointer by the motion of said indicating pointer in one direction, a friction drive for moving said sleeve and said registering pointer in the direction opposite to that in which it is moved by said indicating pointer, and a relatively low speed gear intermediate said spindle and said friction drive.

In testimony whereof I affix my signature in the presence of two witnesses.

LESTER C. DUNCAN.
